UNITED STATES PATENT OFFICE.

EMIL GATHMANN, OF BALTIMORE, MARYLAND.

INGOT-MOLD.

1,246,738.

Specification of Letters Patent. Patented Nov. 13, 1917.

Original application filed February 27, 1913, Serial No. 751,006. Divided and this application filed June 30, 1913. Serial No. 776,544.

To all whom it may concern:

Be it known that I, EMIL GATHMANN, a citizen of the United States, residing in Baltimore city and State of Maryland, have 5 invented certain new and useful Improvements in Ingot-Molds, of which the following is a specification.

The application for this patent is a division of my application for Patent No. 10 751,006 filed February 27, 1913, the claims in said application being confined to the ingot. This invention relates to the manufacture of ingots which shrink during solidification and particularly to the manufacture of ingots of 15 crucible or high grade steel or alloys.

It has been found by numerous experiments that when the mold cavity is larger at its upper than at its lower end and gradually tapers toward the lower end where the 20 cross section is smaller, the lower portion of the ingot freezes or solidifies more quickly as less heat units are contained therein than in the larger portion of the ingot. This tapering of the ingot should be progressive 25 but uniform, *i. e.*, there should not be any sudden change in taper as that might cause the ingot to hang at some point of the mold. With the ordinary tapered ingot for crucible 30 steel practice, tapered sufficiently to materially reduce the depth of pipe, considerable difference in area between the upper and lower part of the ingot is necessary. Furthermore difficulty has been encountered in 35 stacking and piling ingots for storage on account of their varying dimensions from end to end, and it has also been found somewhat difficult to work such ingots under the steam hammer or hydraulic press. Notwithstanding these objections such ingots have been and are now very extensively used.

It has been my experience that the freezing or solidifying of an ingot, which has been practically deoxidized or "killed" in the mold, depends upon the shape of the horizontal cross section of the ingot at various planes from the top to the bottom, and also upon the thickness and consequent heat absorptive power at various parts of the mold.

In the new type of ingot made from my improved mold it is essential that there be considerable lag in the cooling of the upper portion thereof compared with the time of freezing of the lower portion, hence the least distance from the vertical central axis of the ingot to the side walls thereof is made much

less at the bottom of the ingot than at any other point and this distance progressively increases toward the top of the ingot. In the ordinary "big end up" ingot, as heretofore made, where sufficient taper or differential in distance from the vertical axis to the surface of the ingot is given to accomplish any substantial reduction in depth of pipe, the actual cross sectional area of the lower part of the ingot is much less than at 60 the upper part thereof. Hence the depth of pipe does not truly indicate the actual volume or weight of cropping necessary to obtain physically sound steel.

By my improvements I produce tapered 70 ingots with less difference in the upper and lower cross sectional area than would ordinarily be the practice to obtain like results, and such ingots may be readily and uniformly stacked and worked under the hammer and press and which, where the steel or alloy has been degassed by suitable previous treatment, are practically free from pipe or blow-holes.

By my improvements also I obtain practically uniform section of the ingot in certain longitudinal planes, but a decreased section from the top toward the bottom of the ingot with consequent change of dimensions in other longitudinal sections. This I do by 80 so forming the mold cavity as to leave some of the sides of the ingot practically straight and parallel, while others are considerably tapered, or are tapered relatively to the other sides, or given a more pronounced 85 taper than the other sides. Although the freezing or mode of solidification of the liquid steel or alloy, which shrinks or contracts during such cooling and solidification, depends to a considerable extent upon the 90 cross sectional area of the ingot, it depends more particularly upon the least thickness of the ingot at various horizontal planes thereof and also upon the relative heat absorptive power of the walls of the mold in 95 various horizontal planes.

In the accompanying drawings,

Figure 1 shows a vertical central section through an ingot mold embodying my improvements.

Fig. 2 shows a top plan view thereof.

Fig. 3 shows a section on the line 3-3 of Fig. 1.

Fig. 4 shows a side elevation of one section of the mold.

110

The mold shown in the drawings is a sectional mold being divided vertically or longitudinally. This is the preferred form although not essential as various constructions of mold may be used to produce the desired ingots which are not made in section. Where not made in sections the mold cavity should be tapered on all sides to such an extent as to permit the easy withdrawal of the ingot, but two of the sides should be tapered to a greater extent as will be hereinafter described. The walls of the mold are made relatively thick in the lower portion thereof at B and relatively thin at the upper or neck portion B', as by such construction the lower portion of the mold absorbs heat rapidly from the ingot, while the thin portion or neck is less absorptive. In this way the pipe which ordinarily forms in the process of manufacture is forced to the top where it disappears or dwells near the upper portion of the ingot leaving a relatively small end and area to be cropped. When the mold is made in sections, as shown, suitable devices are employed for securing them together.

When an ingot is being cast in a mold such as shown heat will radiate rapidly to the thick walls of the mold where it will be quickly absorbed, while the wider portion at the top of the ingot will cool more slowly and the thin walls B' being less absorbent

will conserve the heat of the ingot at the top. The extreme lower end of the mold cavity may be slightly rounded as shown. 85

It will be observed that the walls B of the lower portion of the mold at opposite ends of the longer diameter of the mold cavity are of substantially the same thickness and the walls B' on opposite sides of the smaller 40 diameter of the mold cavity are of substantially the same thickness and are thicker than the walls B.

I claim as my invention:—

1. A mold having a cavity which is of 45 substantially square horizontal cross section at its upper portion and substantially oblong in horizontal cross section at its lower portion.

2. A mold having a cavity which is of 50 substantially square horizontal cross section at its upper portion and substantially oblong in horizontal cross-section at its lower portion, the mold walls on the opposite sides of the smaller diameter of the cavity being 55 thicker than the remaining or intervening walls.

In testimony whereof, I have hereunto subscribed my name.

EMIL GATHMANN.
